JOINT STARTER AND THROTTLE CONTROL

Charles A. Chayne, Flint, Mich., assignor, by
mesne assignments, to General Motors Cor-
poration, Detroit, Mich., a corporation of
Delaware

Application August 17, 1933, Serial No. 685,519

12 Claims. (Cl. 123—179)

The present invention relates to an internal combustion engine control comprising an engine starter control coordinated with a control for the engine fuel valve. It is among the objects of the invention to provide a coordinated control of the type referred to in which a single operating member is employed to render the starting motor operative to crank the engine and to place the fuel valve in the most advantageous position for starting the engine, said control being so constructed and arranged that, when the control member is released to stop the operation of the starting motor, the fuel valve will automatically be moved to a position most advantageous for the running of the engine during the warming up period. In this connection it is a further object to provide for controlling the fuel valve independently of the engine starter control.

Further objects and advantages of the present invention will be apparent from the following description, reference being had to the accompanying drawing, wherein a preferred embodiment of one form of the present invention is clearly shown.

25 In the drawing:

The figure of the drawing is a wiring diagram illustrating the use of the present invention and is in part the longitudinal sectional view of the controller embodying the invention.

30 Referring to the drawing, a generator 20 is connected to a storage battery 21 through a cut-out relay 22 and a wire 23. The starting motor 24 for the engine is connected with the storage battery through a wire 23 and an electro-magnetic switch 35 25 having a magnet coil 26 which is connected to the wire 23 by an ignition switch 27 and by a second switch included in the controller which will now be described.

The controller comprises a frame 30 having a sleeve 31, the threaded portion of which extends through an instrument board 32 and receives a nut 33 for securing the frame to the board. The frame 30 insulatingly supports stationary contacts 34 and 35 connected, respectively, by wires 36 and 37 with the magnet coil 26 and ignition switch 27. The contacts 34 and 35 are engageable by a movable contact 38 insulatingly carried by a sleeve 39 which extends through the sleeve 31 and is secured to a handle or knob 40. The sleeve 39 is slidable upon a tube 41 integral with a bracket 42 secured by screws 43 to the bracket 30. The tube 41 supports a slidable rod 44 attached to a Bowden wire 45 slidable within a Bowden wire tube 46 attached to the tube 41. The wire 45 is connected with a lever 47 for operating

a fuel valve 48. A spring 49 urges the valve 48 toward closed position. The rod 44 is operated by a handle or knob 50 having a flange 51 engageable by the end of the sleeve 39.

To start the engine, the operator first closes the ignition switch 27 and then pulls the knob 40 toward the right thereby causing the movable contact 38 to move into engagement with the stationary contacts 34 and 35 against the action of a spring 52. The circuit of the coil 26 being completed, the electro-magnetic switch operated by said coil is closed in order to connect the starting motor 24 with the battery. The movement of the knob 40 to close the switch 35, 38, 34, will cause the knob 50 to move in the same direction thereby causing the valve 48 to move into open position indicated at 48b which position has been predetermined to be the most advantageous for starting the engine. As soon as the engine becomes self-operative the operator will release the knob 40 thereby permitting the spring 52 to separate the contact 38 from the contacts 34 and 35 and to return the knob 40 to normal position against the end of the sleeve 41. The circuit of the coil being broken, the electro-magnetic switch 32 will open the circuit of the starting motor 24.

The spring 52 however, does not effect the return of the knob 50 to normal position. The return of the knob 40 to normal position permits the spring 49 to move the wire 45 toward the left in the drawing in order to move the valve 48 toward closed position. The valve 48, however, does not move entirely to the normal position but stops automatically at some position as at 48c which has been selected as being the most advantageous during the warming-up period of the engine. The valve 48c is caused to stop at this position due to the fact that, as the rod 44 moves from its extreme right hand toward its extreme left hand position its motion will be arrested when a groove 55 provided by the rod 44 passes into alignment with two spring urged balls 56 carried by a bracket 42. When these balls 56 are moved into the groove 55, the resistance offered thereby is sufficient to overcome the spring 49. Hence, the valve 48 is not returned to its normal position 48a but stops at its intermediate position 48c. After the engine has been operating for time sufficient to insure its further operation at idling speed, the knob 50 is pushed toward the knob 40 by the operator so that the valve 48 may be returned to position for engine idling.

It will be noted that in the drawing the manually operable switch which is closed by opera-

tion of the button 40 is arranged to close the circuit through an electromagnetic switch 25 which is the main starting motor switch. However, it will be understood that if so desired, the 5 manually operated switch could be the main starting motor switch itself and the magnetic switch could be eliminated. All that it would be necessary to do to accomplish this purpose would be to connect the wire 37 to the wire 23 leading 10 to the battery and connect the wire 36 leading from the contact 34 directly to the starting motor instead of to the winding of the magnetic switch 25. The form shown in the drawing is a preferred form of the invention, but the other construction above referred to could be utilized just 15 as well if it were not desired to use the magnetic switch to control the starting motor circuit.

While the form of embodiment of the present invention as herein disclosed, constitutes a preferred form, it is to be understood that other forms might be adopted, all coming within the 20 scope of the claims which follow.

What is claimed is as follows:

1. Control apparatus for internal combustion engines comprising a starting motor, a current source adapted to supply current to said motor, a switch controlling the connection of said current source with said starting motor, a hand operated device for operating the switch, a fuel control 25 valve for regulating the supply of fuel to the engine, a hand operated member for operating said fuel control valve, said hand operated member being engageable by said hand operated switch operating device as the switch is closed to 30 simultaneously position the fuel valve when the control switch for the starting motor is closed.

2. Control apparatus for internal combustion engines comprising a starting motor, a current source adapted to supply current to said motor, a switch controlling the connection of said current source with said starting motor, a hand operated device for operating the switch, a fuel control 35 valve for regulating the supply of fuel to the engine, a hand operated member for operating said fuel control valve, said hand operated member being engageable by said hand operated switch operating device as the switch is closed to simultaneously position the fuel valve when the control switch for the starting motor is closed, 40 and means whereby the hand operated fuel control member may be operated independently of the switch operating device.

3. Control apparatus for internal combustion engines comprising a starting motor, a current source adapted to supply current to said motor, a switch controlling the connection of said current source with said starting motor, a hand operated device for operating the switch, a fuel control 45 valve for regulating the supply of fuel to the engine, a hand operated member for operating said fuel control valve, said hand operated member being engageable by said hand operated switch operating device as the switch is closed to simultaneously position the fuel valve when the control 50 switch for the starting motor is closed, and means whereby the switch operating device may be returned to normal switch open position without corresponding movement of the fuel control member.

4. Control apparatus for internal combustion engines comprising a starting motor, a current source adapted to supply current to said motor, a switch controlling the connection of said current source with said starting motor, said switch 55 being mounted on a fixed support convenient to

the operator and comprising fixed and movable contacts, a hand operated member movably mounted in said support carrying said movable contact, a fuel valve for variably regulating the engine fuel supply, a manually operable member for moving said valve, said member being in the path of movement of the hand operated switch closing member whereby when the movable contact is moved to close the switch the fuel control valve is operated to supply the desired amount 10 of fuel to the engine.

5. Control apparatus for internal combustion engines comprising a starting motor, a current source adapted to supply current to said motor, a switch controlling the connection of said current source with said starting motor, said switch being mounted on a fixed support convenient to the operator and comprising fixed and movable contacts, a hand operated member movably mounted in said support carrying said movable contact, a fuel valve for variably regulating the engine fuel supply, a manually operable member for moving said valve, said member being in the path of movement of the hand operated switch closing member whereby when the movable contact is moved to close the switch the fuel control valve is operated to supply the desired amount of fuel to the engine, and means for movably supporting the fuel valve operating member so constructed as to permit movement of the said member independently of the switch closing member.

6. Control apparatus for internal combustion engines comprising a starting motor, a current source adapted to supply current to said motor, a switch controlling the connection of said current source with said starting motor, said switch being mounted on a fixed support convenient to the operator and comprising fixed and movable contacts, a hand operated member movably mounted in said support carrying said movable contact, a fuel valve for variably regulating the engine fuel supply, a manually operable member for moving said valve, said member being in the path of movement of the hand operated switch closing member whereby when the movable contact is moved to close the switch the fuel control valve is operated to supply the desired amount of fuel to the engine, and means for returning the fuel valve operating means to normal position when the switch closing member is returned to initial 50 position.

7. Control apparatus for internal combustion engines comprising a starting motor, a current source adapted to supply current to said motor, a frame mounted on a fixed support convenient to the operator, a starter switch including fixed contacts carried by said frame, a member slidably mounted in said frame carrying a movable contact and having a button on one end for hand operation by the operator, a fuel control valve for regulating the engine fuel supply, a manually operable member slidably mounted in said frame for operating said fuel valve and having a button on one end for manual operation, said button being in the path of movement of the button on the switch operating member, whereby when the switch is closed the fuel control valve is moved by the switch closing member to regulate the fuel supply during starting.

8. Control apparatus for internal combustion engines comprising a starting motor, a current source adapted to supply current to said motor, a frame mounted on a fixed support convenient to the operator, a starter switch including fixed contacts carried by said frame, a tubular member

- slidably mounted on said frame carrying a movable contact and having a button on one end for hand operation by the operator, a fuel control valve for regulating the engine fuel supply, an operating rod for said fuel supply valve slidably mounted in said tubular member, an operating button on one end of the rod adapted to be engaged by the button on said switch operating member when the latter is moved to close, whereby the fuel valve is operated to supply the desired amount of fuel during the starting of the engine.
9. Control apparatus for internal combustion engines comprising a starting motor, a current source adapted to supply current to said motor, a starter switch connecting the motor with said current source, a second switch for controlling the operation of said first named switch, a hand operable device for operating said control switch, a fuel control valve for regulating the supply of fuel to the engine, a hand operable member for operating said fuel control valve, said member being engageable by said hand operated switch closing device, as the switch is closed to simultaneously position the fuel valve in position to supply the desired amount of fuel as the control switch is closed.
10. Control apparatus for internal combustion engines comprising a starting motor, a current source adapted to supply current to said motor, a frame mounted on a fixed support convenient to the operator, a starter switch including fixed contacts carried by said frame, a tubular member slidably mounted on said frame carrying a movable contact and having a button on one end for hand operation by the operator, a fuel control valve for regulating the engine fuel supply, an operating rod for said fuel supply valve slidably mounted in said tubular member, an operating button on one end of the rod adapted to be engaged by the button on said switch operating member when the latter is moved to close, whereby the fuel valve is operated to supply the desired amount of fuel during the starting of the engine, said rod being movable independently of the switch operating member, in order to variably control the position of the fuel valve while the switch operating member is stationary.
10. Control apparatus for engines of automotive vehicles comprising a starting motor, a current source adapted to supply current to said motor, a frame mounted on the dash of the vehicle, a starter switch including fixed contacts carried by said frame, a movable contact adapted to engage said fixed contacts to close said switch, a hand operated member movably mounted on the frame and adapted to operate said movable contact, a fuel valve for controlling the fuel supply, a movable member for operating said fuel valve disposed in the path of said hand operated member so that when the latter is moved to close the switch the valve operating member will be moved thereby to a position to supply the desired amount of fuel during the starting operation.
11. Control apparatus for internal combustion engines comprising a starting motor, a current source adapted to supply current to said motor, a starter switch connecting the motor with said current source, a second switch for controlling the operation of said first named switch, a hand operable device for operating said control switch, a fuel control valve for regulating the supply of fuel to the engine, a hand operable member for operating said fuel control valve, said member being engageable by said hand operated switch closing device, as the switch is closed to simultaneously position the fuel valve in position to supply the desired amount of fuel as the control switch is closed.
12. Control apparatus for internal combustion engines comprising a starting motor, a current source adapted to supply current to said motor, a starter switch connecting the motor with said current source, a second switch for controlling the operation of said first named switch, a hand operable device for operating said control switch, a fuel control valve for regulating the supply of fuel to the engine, a hand operable member for operating said fuel control valve, said member being engageable by said hand operated switch closing device, as the switch is closed to simultaneously position the fuel valve in position to supply the desired amount of fuel as the control switch is closed, and means operable to return the fuel valve operating member to normal position when the switch closing device is returned to initial position.

CHARLES A. CHAYNE.
